UNITED STATES PATENT OFFICE.

FRANZ BRÜCKNER, OF BURG, NEAR MAGDEBURG, GERMANY, ASSIGNEE TO JAMES F. DORAN, OF DANBURY, CONNECTICUT.

BLOWING MACHINE FOR THE MANUFACTURE OF FELT HATS.

Application filed November 16, 1922. Serial No. 601,218.

The material which is principally used for the manufacturing of felt hats is hares' hair and rabbits' hair which must be separated from the skin according to different well known methods and prepared so that it is perfectly clean, which means free from coarse admixture, waste skin, coarse prickly hair and pieces of leather and so that it is loose and does not form balls nor is entangled.

For the treatment of the hair blowing machines are preferably used in which the hair is combed by means of the so-called picker cylinder and blown by the air current produced by the rapid rotation of said cylinder into a chamber in which it drops upon a conveying cylinder as soon as it gets out of the range of the air current, to be conducted to a second, third, fourth, fifth and eventually some more picker cylinders until it is sufficiently cleaned and ready for use. The blowing machines of known type possess however serious inconveniences which unfavorably influence their effect and efficiency. The hair thrown up by the picker cylinder becomes easily entangled in the wire gauze covers of the several boxes where it is retained by the air current. At these points balls of hair are formed which have to be removed, or they drop off as soon as they have become heavy enough. In the latter case the picker cylinders cannot work properly this large mass of hair. The accumulations of hair in the wire gauze prevent further the regular outflow of dust so that consequently, besides the irregular working resulting from the over-loading of the picker cylinders, one of the main objects, the thorough removal of dust from the hair, is not realized.

It has been proposed to avoid this inconvenience by arranging upon the outer side of each wire gauze cover one or several sieve-like surfaces, which, operated mechanically, beat continuously against the outer side of the wire gauze covers. These beaters, which by the draft produced in a direction opposite to that of the air current flowing upward in the boxes, are designed to prevent the settling of the hair upon the wire gauze cover are objectionable in that they impede the regular draught which is necessary for the removal of the dust since by the wind, produced by the beaters, eddies are produced in the upper part of the box which act against

the escape of the dust. After the beaters have been used for some time they become full of dust and small hair so that they no longer present perforated surfaces but solid surfaces which swing towards the wire gauze covers so that the production of counter wind in the box is increased. A further inconvenience is that the dust can no longer escape through these solid surfaces of the beaters and is consequently always driven back.

The present invention overcomes these inconveniences. In one embodiment of the invention the cover itself, it may be of any shape whatsoever, is moved in order to prevent the accumulation of hair. The movement can be a shaking motion consisting of a reciprocating movement in vertical or in horizontal direction, or it may be produced by a continuous movement of the surface or, if the cover is drum-shaped, it may consist in a continuous revolving motion of the drum, or the like. In order to avoid any possibility of accumulating of hair one or more ducts of suitable construction (elastic sheet iron, brush rollers, hoes or the like) may be provided, moving in opposite direction relative to the perforated surface so that owing to this invention disturbances of service or unequal working of the machine are absolutely avoided. Other objects or aims of the invention will be in part obvious or in part pointed out hereinafter.

The invention accordingly consists in the features of construction, the combinations of elements and arrangements of parts all as will illustratively be described herein, and the scope of the application of which will be indicated in the following claims.

In the accompanying drawing in which are shown one or more various possible embodiments of the several features of this invention:

Fig. 1 is a vertical longitudinal section through the middle of a three-cylinder machine in which each blowing box is covered by a drum.

Fig. 2 shows a similar machine as Fig. 1 the wind boxes being covered by an endless band.

Fig. 3 shows a machine in which the cap-shaped cover is continuously raised and lowered.

Fig. 4 is a cross section of Fig. 3.

Fig. 5 shows in cross section a blow pipe.

Figure 6 is a vertical longitudinal sectional view illustrative of a possible embodiment of certain features of this invention; and

Figures 7 and 8 are similar views illustrative of other possible embodiments of certain features of this invention.

Similar reference characters refer to similar parts throughout the several views of 10 the drawing.

The machine is built in the well known manner upon an under-frame which carries also a driving mechanism for the picker disks and the lateral driving shaft mounted in longitudinal direction. The under-frame is generally known and has nothing to do with the present invention so that it has not been illustrated on the drawing. Between the two walls of the under-frame

20 the hair box 10 is mounted. The hair box is closed at the top end by a perforated surface which has narrow holes for the escape of the air. These covering surfaces are continuously moved from any convenient part

25 of the machine, or a reciprocating motion in vertical direction or horizontal direction is communicated to the same. This perforated cover can consist, as shown in Fig. 1, of a narrowly meshed cylinder 11 which

30 revolves continuously around an axle 12. The cylinder is partly located in an aperture of the top plate of the wind box. The hair is fed for instance by hand with the aid of the feeding table 13, driven from one

35 of the cylinders 14 or 15. The pulling-in cylinders 16 and 17 rotate in the well known manner in bearings which are laterally mounted upon the frame walls. They are driven from the main driving mechanism from the under-frame from which the conveying cylinders 18 are also driven. These conveying cylinders 18 are journalled in a similar manner as the pulling-in cylinders, in corresponding bearings of the frame

40 walls. Upon each of the axles of the conveying cylinders a rope pulley 19 is keyed which is connected by rope 20, roller 21 and axle 12 with each cylinder 11. Instead of the rope drive any other driving mechanism, such as belt drive, chain drive or toothed wheel gear can be used. The axles 12 of the drums 11 rest in bearings which are for instance fixed upon the lateral wooden walls of the hair box 10. The picker

45 cylinders 22 are driven, as are the pulling-in cylinders and the conveying cylinders from the driving mechanism in the under-frame. The two pulling-in cylinders are spring-controlled or weight-controlled so that they are pressed upon one another with the pressure which is required for the pulling-in of the hair.

The pulling-in cylinders 16, 17, conveying cylinders 18 and feeding cylinders 14 and

15 revolve very slowly and all at approximately the same circumferential speed. The sieve-drums 11 revolve more rapidly and the circumferential speed of the same can be regulated if required by stepped disk arrangements which are however not shown 70 on the drawing. The picker cylinders revolve with a very high circumferential speed and they present numerous projecting pointed studs. In the upper part of the wind box 10 a ductor 23 is arranged designed 75 to scrape off the hair which sticks to the covering drum; said ductor being preferably made from elastic steel sheet, but may comprise cylindrical brushes or the like.

In Fig. 2 a second form of construction is 80 shown in which the movable covering surfaces for the wind boxes consist of an endless perforated band 24 which covers several or all wind boxes. This perforated band is guided over rotating cylinders 25 so that it 85 is moved continuously in horizontal direction over the wind boxes. Upon the upper edge of each partition which separates the several wind boxes from one another a ductor 23 is arranged which is designed to 90 scrape off the hair drawn along by the endless band and to throw this hair back into the corresponding wind box and upon the picker cylinder. One of the cylinders 25 for the endless band 24 is driven, as shown 95 on the drawing, by belt or similar transmission, from a belt pulley 26 keyed upon the axle 27 of the conveying cylinder 18.

Instead of the endless perforated band 100 perforated or sieve-like plates can be used for covering the wind boxes, said plates being continuously shaken in order to disengage the hair from the same. This form of construction is not shown on the drawing 105 as it will be easily understood even without illustration.

Figs. 3 and 4 show a further form of construction according to which the movable sieve-like surfaces are constructed so that they are like the caps used with the machines of known construction. According to the invention several or all wind boxes 110 are covered by a common movable cap 28. The wind boxes are separated the one from the other by partitions 29. A continuous 115 movement can be communicated to the cap or caps for instance by the following arrangement. Upon the shaft 30 of one of the conveyor cylinders a belt or rope pulley 1 is mounted which, as shown in Fig. 4, transmits the rotating movement by means of a counter pulley 2 upon a cam disk 3 fixed upon the axle of the counter pulley. This cam disk is designed to come in contact with a pin 4 downwardly projecting from the 120 movable cap 28. The movable cam disk 3 raises the cap slowly so that it oscillates around the hinges 5 for a distance 6 indi-

cated in Fig. 4, whereupon the cap being suddenly released drops back upon the wind box. The shock which is produced by the cap dropping back into position is sufficient to make the hair drop off which has stuck to the inner surface of the cap. In order to prevent the hair escaping through the gap which is formed with the raised caps, plates 7 arranged upon the partitions cover said 10 gaps. A ductor or scraping device is not required as the movable parts do not execute a sliding movement.

The operation of the improved blowing machine is as follows: The hair to be cleaned 15 is spread out by hand or by an automatic device upon the feeding table 13 which feeds the material to the pulling in cylinders 16, 17. The material gripped by these pulling-in cylinders 16 and 17 is securely held, in 20 consequence of the loading of said cylinders, to be released gradually at the other side of the cylinders. The studs of the picker cylinder, which revolves with high speed, grip the hair coming out from the pulling-in cylinders 25 whilst the hair is still being held by these pulling-in cylinders. The hair is thus combed and loosened and solid admixtures are removed from the hair. After the hair has been completely released by the pulling- 30 in cylinders it is drawn along by the picker cylinder and blown up by the air current produced by the rapid rotation of the picker cylinder so that it flows up in the wind box. Heavy hair is directly thrown tangentially 35 downward from the picker cylinder to form the waste. As soon as the hair comes from the picker cylinder no other work has to be done but to separate the hair from the air current. This is effected in such a manner 40 that the air with the dust particles escapes through the perforated cover consisting either of the perforated drum 11, the endless perforated band 24, the perforated movable cap 28; the hair dropping back from 45 this perforated cover. The perforated drum 11 (Fig. 1) revolves in the direction of the arrow and conducts the hair thrown against the outer surface of the drum towards the ductor 23 which scrapes the hair off the 50 outer surface of the perforated drum so that it drops down perpendicularly upon the pulling-in cylinders for the next following wind box. Part of the hair flowing up in the wind box drops down before it can reach 55 the perforated cover, this hair drops upon an airtight conveying cylinder 18 designed to conduct the hair to the pulling-in cylinders 16, 17 of the next following wind box. As many wind boxes can be arranged in suc- 60 cession as required.

Owing to this working method any disturbance caused by accumulation of hair and by irregular charging of the picker cylinders resulting therefrom are avoided and 65 the hair is thoroughly freed from dust so

that a perfect result is obtained without any interruption of service.

In the blowing machines of known construction the hair traverses successively, on the average, 10 to 12 wind boxes before it 70 is ready for use. This is generally done in such a manner that the hair traverses twice a blowing machine composed of 5 or 6 wind boxes. The improved construction of such machines comprising very short wind boxes 75 permits the combination of 10 to 12 and even more wind boxes in one machine which is nevertheless not of excessive length. It is not necessary to use so many wind boxes in order to separate the prickly hair completely from the soft hair. Hitherto only the picker cylinders, which loosen and sort the hair, were used for this purpose. The hair is however already loosened so much when coming from the second or third wind box 80 or picker cylinder that scarcely 1% of unloosened hair will remain and this 1% consists mostly of very small entangled knots which generally are not even entirely loosened when the hair comes from the twelfth 85 picker cylinder. On the other hand the remaining 99% loose hair must also go over the other picker cylinders although it has been already thoroughly loosened and made ready. These 99% of hair ought merely to 90 be sorted. By making this hair nevertheless pass another 8 to 10 times over the rapidly revolving picker cylinders with steel pickers it is frequently damaged so that valuable material is lost. 100

In order to avoid these inconveniences and according to certain features of this invention the working process in the machine is separated into two parts, the first part being designed for the usual loosening and sorting of the hair and the second part serving for the sorting. During the first part of the treatment the hair is loosened by the picker cylinders and the heaviest parts of the hair are separated whilst the prickly unloosened 105 hair does not participate in the second part of the working. Figs. 3 and 5 relate to this improved working method.

The blowing machine is composed of three wind boxes as hereinbefore described and shown, only the first two wind boxes being used for loosening the hair, the third wind box serving exclusively for the sorting. Only this last wind box is of somewhat different construction than the others. For the picker cylinder a stationary blowing pipe 31 is substituted through which flows a light air current produced by a fan mounted in the machine. The blowing pipe 31 which has a slit 32 (Fig. 5) extending over its 110 entire length is surrounded by a sleeve 33 having a nozzle 34. The sleeve 11 is of slightly greater diameter than the blowing pipe and arranged so that it can be easily turned around said blowing pipe. Opposite 115

120 125 130

the blow pipe a solid baffle plate of convenient shape is arranged so that it can be oscillated or displaced.

The operation of the machine is in the first two wind boxes as described above whilst in the third wind box the hair is brought by the pulling-in cylinders 16 and 17 in proximity to the orifice of nozzle 34 of the blowing pipe. This orifice of the nozzle 10 is adjusted at a convenient angle and distance with regard to the opposite baffle plate. The baffle plate 35 could be omitted so that the hair is blown directly against the conveying cylinder 18.

15 The light useful hair flows, as shown in Fig. 3, up in the wind box and the heavy useless hair and knots drop down. The adjustable baffle or catch plate 35 in combination with the imperforate conveying cylinder 18 guides the material so that no eddies are produced as is apt to occur when perforated conveying cylinders are used. Owing to this last described improvement fewer picker cylinders are required and the hair 25 is more effectively treated so that the dust can be removed from the hair much more rapidly than hitherto. This improvement constitutes a great saving in pickers and mechanical parts connected with the same.

30 Figure 6 shows another form of construction of a blowing machine according to my invention, and it will be noted that the construction is substantially similar to that specifically illustrated in Figure 1 excepting that the pulling-in cylinders associated with one of the wind boxes and their corresponding picker roll are replaced by a blowing pipe 31—34 and a pair of pulling-in cylinders for supplying fur to be acted upon by this blowing pipe; more specifically, it will be noted that in the construction shown in Figure 6 each of the wind boxes has associated with it a sieve drum 11, preferably arranged to form a cover for the box, and that the sieve drum associated with each wind box is given a continuous movement, as by rotation thereof, but in a direction so that the surface upon which hair is deposited is carried in a direction toward the next succeeding wind box. The blowing pipe 31 (substantially of the construction hereinbefore described in connection with Figures 3 and 5) is arranged to blow the hair supplied to it by the pulling-in cylinders 16—17 against the conveying cylinder 18, the latter acting to break up the air current so that the light hair flows up into the wind box and the heavy prickly hair and entangled hair drops upon the bottom of the wind box.

60 In Figure 7 I have illustrated another possible mode of carrying out certain features of my invention, and it will be noted that the construction illustrated in this figure is substantially similar to the construc-

tion shown in Figure 6, excepting that I have included an adjustable solid or imperforate baffle plate 35 against which the air current of the blowing pipe 31 is broken so that the light hair flows up into the wind box and the heavy prickly hair and entangled hair drops upon the bottom of the wind box. While the conveying cylinder 18 in the relation shown in Figure 6 may act effectively under certain conditions 70 to break up the air current in the desired manner and to achieve the desired results, yet, in order that the varying conditions of practical use may be more readily met, the adjustable baffle plate 35 (shown by way of 75 example as substantially of similar construction to that shown in Figure 3) may permit an exact and nice predetermination of the manner in which the air current is broken up and its components directed. The 80 adjustability of the blow pipe 31, as hereinabove described in connection with Figure 3, may further be brought into action in conjunction with the adjustability of the baffle plate 35 to achieve the intended 85 directing of the components of the air current thus broken up, and in conjunction with a coacting perforated and moving surface, such as is provided by the sieve drum 11, the path of movement of the upwardly directed air current and correspondingly the path of movement of the light hair carried upwardly thereby, may be predetermined to achieve a distribution of the deposit of the hair upon the perforated moving surface in 90 a manner best adapted to meet the conditions of practical use, the moving perforated surface acting furthermore to insure a uniform transfer of hair to the pulling-in cylinders associated with the exit pulling-in 95 cylinders of the wind box.

100 In Figure 8 I have illustrated an arrangement in which each of the wind boxes is provided with a sieve drum 11, preferably arranged to form a cover for the 110 wind box, and rotated in the manner indicated in Figure 1 so as to be given a continuous movement of its effective surface exposed to the path of movement of the hair in a direction from the entrance end of the wind box toward the exit end of the wind box. A picker cylinder is associated with each wind box and adjacent the pulling-in cylinders thereof so as to act, in a 115 manner which will be clear from what has hereinbefore been set forth in connection with Figure 1, to produce an air current and to throw the hair into the hair box. While the imperforate conveying cylinder 120 18 as shown in Figure 1 may act effectively, under certain conditions of practical use, to insure an appropriate directive movement of the air current produced by the rapid rotation of the picker cylinder so that it 125 flows up into the wind box and carries the 130

light hair with it, yet I prefer to include, in order to meet other conditions of practical use, an adjustable baffle plate 35 (see Figure 8) positioned, for example, in front 5 of the conveying cylinder 18 and thus adapted to regulate the direction of movement of the hair.

The action of this baffle plate is such that in the first place the movement in an upward direction of the light hair, resulting either from the throwing action of the picker cylinder or by virtue of the air current produced thereby, may be regulated as to its direction so that the depositing of hair 10 upon the moving surface of the sieve drum 11 may be exactly predetermined; the sieve drum 11, rotating in the direction indicated in the drawings, insures a steady and uniform transfer of deposited hair in a direction 15 from the entrance end of the wind box toward the exit end of the wind box, thereby not only insuring continuity and uniformity of action, since a relatively permanent accumulation of hair on the 20 perforated surface is prevented, but also and by virtue of the direction of the movement of the perforated surface insures a speeding up of the operation of each wind box as well as an avoidance of interference with the 25 upwardly moving hair or the air currents producing such movement.

While the construction and action of the sieve-like surfaces shown in Figures 3 and 4, according to which they are like the caps used with the machines of known construction, but made to be raised and suddenly dropped by the action of the cam disk 3, as hereinbefore described, achieves a number of thoroughly practical advantages, yet it will 30 be noted that the sieve-like surfaces provided in such a construction, while they prevent accumulation of hair thereon due to the tendency of the hair to adhere to the inner faces of the perforated surfaces, they do 35 not make possible the achievement of the many thoroughly practical advantages which may be realized where the sieve-like surface is arranged as is typified, for example, in Figures 1, 2, 6, 7 and 8, wherein 40 the perforated surface moves in the direction toward the exit end of each wind box. With the constructions typified in these latter figures, and as will be clear from what has already been set forth in connection 45 therewith and more particularly in connection with Figures 1 and 2, the accumulation of hair and irregular charging of the subsequent picker cylinders with the resultant disturbance are avoided, but it will also be 50 seen that (see, for example, Figure 1) the hair which is made to drop from the moving surface of the sieve drums 11 is first carried by the movement of the surface of the sieve drum out of range of the upwardly directed 55 air current produced by the picker cylinder 60

and hence out of range of the upwardly moving hair carried by this air current; interference, as by hair dislodged from the perforated surface or cover (as may take place with the construction shown in Figures 3 and 4) with the upwardly moving hair is thus effectively prevented, greater regularity is achieved with consequent uniformity of action, and likewise greater speed of operation achieved. These are a few of 70 the practical advantages which are achieved by the preferred embodiment of certain of the features of this invention.

By the improved construction of the perforated covers of the wind boxes as hereinbefore described and shown in the drawings any disturbance by accumulation of hair and by irregular loading of the picker cylinders is avoided and a thorough removal of dust from the hair is assured so that the most 75 perfect result is obtained without any interruption of service, a considerable saving in energy being further obtained by the improved construction of the third wind box 80 which has just been described.

As various possible embodiments might be made of the above invention and as various changes might be made in the embodiments shown, it is to be understood that all matter described above and illustrated in the accompanying drawing is to be interpreted 85 as illustrative and not in a limiting sense.

I claim:—

1. In a blowing machine for fur, in combination, a wind box, a second wind box, said 100 first wind box having fur-confining walls free from stationary perforated portions, means adapted to receive and throw fur into said first wind box and in a general upward direction, means adapted to receive fur from said first wind box and throw it into said second wind box, and a perforated rotatable drum associated with said first wind box and positioned in the path of movement of fur 105 therein and rotatable in a direction to carry fur deposited thereon toward said second-mentioned receiving and throwing means.

2. In a blowing machine for fur, in combination, a wind box, a second wind box, means adapted to receive and throw fur into said first wind box, means adapted to receive said fur from said first wind box and throw the same into said second wind box, and a perforated moving member having one surface exposed outside said wind boxes and its other surface exposed inside said first wind box and against which said fur is thrown in said first wind box and by which it is conveyed toward said last means.

3. In a blowing machine for fur, in combination, a plurality of consecutive wind boxes, means in each of said wind boxes adapted to receive the fur and throw the same thereinto, and moving perforated means covering an opening in each of said 120 125 130 135 140 145 150 155 160 165 170 175 180

- 6 wind boxes adapted to receive on its inner surface said fur thrown thereinto and convey said fur toward the next consecutive wind box.
- 7 4. In a blowing machine for fur, in combination, a wind box, a second wind box, means adapted to receive and throw fur into said first wind box, and a moving screen through which the current of air set up by 10 said fur-throwing means passes to the exterior of said wind boxes and against the surface of which said fur is thrown in said first wind box adapted to convey said fur toward said second wind box.
- 15 5. In a blowing machine for fur, in combination, a wind box, a second wind box, means adapted to receive and throw fur upwardly into said first wind box, means adapted to throw fur into said second wind 20 box, means in said first wind box adapted to receive and position said fur in operative relation to said last means, and a perforated rotating drum in said first wind box above said positioning means therein and 25 against which said fur is thrown therein and from which said fur is adapted to drop upon said positioning means.
- 30 6. In a blowing machine for fur, in combination, a wind box, a second wind box, means adapted to receive and throw fur upwardly into said first wind box, means adapted to throw fur into said second wind box, means in said first wind box adapted to receive and position said fur in operative 35 relation to said last means, and a perforated rotating drum for said first wind box providing a passage to the exterior of said wind boxes for the current of air set up by 40 said fur-throwing means, said perforated drum being mounted above said positioning means and being adapted to receive said fur and deposit it upon said positioning means.
- 45 7. In a blowing machine for fur, in combination, a wind box, a second wind box, means adapted to receive and throw fur upwardly into said first wind box, means adapted to receive and throw fur into said second wind box, a moving member in said 50 first wind box adapted to feed said fur to said throwing means for said second wind box, and a second moving member for said first wind box positioned above said first moving member and perforated, said perforated moving member providing a passage to the exterior of said wind box for 55 the current of air set up by said throwing means and being adapted to receive upon its surface said upwardly thrown fur and deposit it upon said first moving member.
- 60 8. In a blowing machine for fur, in combination, a wind box, means adapted to receive and throw fur thereinto, and a revolving perforated drum opening at its ends 65 exterior of said wind box against the sur- face of which said fur is thrown in said wind box.
9. In a blowing machine for fur, in combination, a wind box, a second wind box, means adapted to receive and throw fur upwardly into said first wind box, means adapted to receive and throw fur into said second wind box, a moving member in said first wind box adapted to feed said fur to said throwing means for said second wind box, and a rotating perforated drum for 70 said first wind box positioned above said moving member, said perforated drum providing a passage to the exterior of said wind boxes for the current of air set up by said throwing means and being adapted to receive upon its surface said upwardly thrown fur and deposit it upon said first moving member.
- 75 10. In a blowing machine for fur, in combination, a wind box, a second wind box, means adapted to receive and throw fur upwardly into said first wind box, means adapted to receive and throw fur into said second wind box a rotating cylinder in said first wind box adapted to feed said fur to said throwing means for said second wind box, and a second rotating cylinder for said first wind box positioned above said first rotating cylinder and perforated, said perforated cylinder forming a passage to the exterior of said wind boxes for the current of air set up by said throwing means and being adapted to receive upon its surface said upwardly thrown fur and deposit it upon said first rotating cylinder.
- 80 11. In a blowing machine for fur, in combination, a plurality of consecutive wind boxes, means in each of said wind boxes adapted to receive and throw fur upwardly thereinto, and a rotating perforated drum in the upper portion of each of said wind boxes, said perforated drums being positioned above said fur-throwing means, providing 85 passages to the exterior of said wind boxes for the currents of air set up by said throwing means and being adapted to catch said fur on their surfaces and carry the same toward the next consecutive wind box.
- 90 12. In a blowing machine for fur, in combination, a plurality of consecutive wind boxes, means in each of said wind boxes adapted to receive and throw fur upwardly thereinto a rotating perforated drum in the upper portion of each of said wind boxes, said perforated drums being positioned above said fur-throwing means, providing 95 passages to the exterior of said wind boxes for the currents of air set up by said throwing means and being adapted to catch said fur on their surfaces and carry the same toward the next consecutive wind box, and means in each of said wind boxes for receiving said fur from said perforated drums and adapted to position said fur for en- 100
- 100 110 115 120 125 130

gagement by said throwing means of the next consecutive wind box.

13. In a blowing machine for fur, in combination, a plurality of consecutive wind boxes, a rotating picker cylinder for each of said wind boxes adapted to receive fur and to throw the heavy material thereof downwardly and the lighter fur thereof upwardly into said wind boxes, and a rotat-
10 ing perforated drum in the upper portion of each of said wind boxes, said perforated drums being positioned above said picker cylinders, providing passages to the exterior of said wind boxes for the currents of air
15 set up by said picker cylinders and being adapted to catch said upwardly thrown fur on their surfaces and carry the same toward the next consecutive wind box.

14. In a blowing machine for fur, in combination, a wind box, a second wind box, means adapted to receive and throw fur into said first wind box, means adapted to receive and throw fur into said second wind box, means in said first wind box adapted
20 to position said fur in operative relation to said last means, a moving perforated member against the surface of which said fur is thrown in said first wind box, and means for removing said fur from the surface of said
25 member to fall upon said positioning means.

15. In a blowing machine for fur, in combination, a wind box, a second wind box, means adapted to receive and throw fur upwardly into said first wind box, means
30 adapted to receive and throw fur into said second wind box, means in said first wind box adapted to position said fur in operative relation to said last means, a moving perforated member in the upper portion of
35 said first wind box against which said fur is thrown therein, and means for removing said fur from the surface of said member to fall upon said positioning means.

16. In a blowing machine for fur, in combination, a plurality of consecutive wind boxes, rotating picker cylinders for each of said wind boxes adapted to receive fur and to throw the heavy material thereof downwardly and the lighter fur upwardly into said wind boxes, pulling-in cylinders for
40 delivering fur to each of said picker cylinders, means in each of said wind boxes for positioning fur in operative relation to the pulling-in cylinders for the next consecutive wind box, and a rotating perforated drum for each of said wind boxes adapted to receive upon its surface said upwardly thrown fur therein and deposit the same upon said positioning means.

17. In a blowing machine for fur, in combination, a plurality of consecutive wind boxes, a picker roll at one end and lower portion of each of said wind boxes and adapted to throw fur into its associated
45 wind box and in a general upward direc-

tion and to cause heavier particles to be cast in a general downward direction, a perforated rotatable drum associated with each of said wind boxes and positioned to receive upwardly thrown fur and rotatable in a direction to carry the fur toward the other end of said wind box, and means for withdrawing fur from said other end of said wind box and feeding it to the picker roll of the next succeeding wind box, each
50 wind box and its associated perforated drum being arranged so that the latter is the only perforated surface into contact with which fur may be thrown.

18. In a blowing machine for fur, in combination, a plurality of consecutive wind boxes, pulling-in cylinders for each of said wind boxes, a picker cylinder adapted to receive hair from the pulling-in cylinders and to throw it in a general upward direction and to cause heavier particles thereof to be cast in a general downward direction, means forming a cover for each of said wind boxes comprising a perforated drum continuously rotatable, an air-tight conveying cylinder positioned substantially opposite the picker cylinder for conducting to the pulling-in cylinders of the next succeeding wind box the hair which drops down from said perforated drum, and an adjustable baffle plate in front of the conveying cylinder adapted to regulate the direction of movement of the hair.

19. In a blowing machine for fur, in combination, a wind box, a second wind box, means adapted to receive and throw fur upwardly into said first wind box, means adapted to throw fur into said second wind box, means in said first wind box adapted to receive and position said fur in operative relation to said last means, a perforated rotating drum for said first wind box adapted to receive upon its surface said upwardly thrown fur and carry the same in a direction toward the second wind box, and means associated with said hair throwing means in said first wind box and adapted to direct the movement of fur thrown thereby.

20. In a blowing machine for fur, in combination, a wind box, a second wind box, means adapted to produce an air current for carrying fur into said first wind box, means adapted to receive and throw fur into said second wind box, a rotating cylinder in said first wind box adapted to feed fur to said throwing means for said second wind box, a second rotating cylinder for said first wind box positioned above said first rotating cylinder and perforated, and means co-acting with said air current producing means and said second-mentioned rotating cylinder for directing the air currents produced by the former.

21. In a blowing machine for fur, in combination, a plurality of consecutive wind

- boxes, a rotating picker cylinder for each of said wind boxes adapted to receive fur, to throw the heavy material thereof downwardly, and to produce an air current adapted to move with it the lighter fur, a rotating perforated drum associated with each of said wind boxes and adapted to receive said lighter fur thereon, said rotating drum being rotated in a direction to carry the fur thereon toward the next consecutive wind box, and means adapted to direct the movement of the air current produced by said rotating picker cylinder.
22. In a blowing machine for fur, in combination, a plurality of consecutive wind boxes, a rotating picker cylinder for each of said wind boxes adapted to receive fur, to throw the heavy material thereof downwardly, and to produce an air current adapted to move with it the lighter fur, a rotating perforated drum associated with each of said wind boxes and adapted to receive said lighter fur thereon, said rotating drum being rotated in a direction to carry the fur thereon toward the next consecutive wind box, a rotating cylinder adapted to receive fur from said perforated cylinder and convey it in a direction toward the picker cylinder of the next succeeding wind box, and imperforate means associated with said last-mentioned rotating drum but spaced therefrom to produce an air passage therebetween.
23. In a blowing machine for fur, in combination, a plurality of consecutive wind boxes, a picker roll at one end and lower portion of each of said wind boxes for throwing lighter particles of fur into its associated wind box and in a general upward direction and adapted to cause heavier particles to be thrown in a general downward direction, said picker roll also producing air currents to assist in the movements of the fur particles, a perforated rotatable drum associated with each of said wind boxes and positioned to receive upwardly thrown fur particles and rotatable in a direction to carry the fur particles toward the other end of said wind box, imperforate means positioned in the path of movement of the air set in motion by the picker roll in each of said wind boxes and adapted to deflect the moving air, thereby to affect the action of the picker rolls, and means for withdrawing fur from the other end of said wind box and feeding it to the picker roll of the next succeeding wind box, each wind box and its associated perforated drum being arranged so that the latter is the only perforated surface into contact with which fur particles may be thrown.
24. In a blowing machine for fur, in combination, a plurality of consecutive wind boxes, means in each of said wind boxes adapted to receive and throw fur particles upwardly thereinto and to throw downwardly heavier fur particles, a perforated rotating drum for each of said wind boxes and positioned to receive upwardly thrown fur particles and rotatable in a direction to carry the fur particles in a direction toward the next succeeding wind box, and an adjustable plate-like member, one for each wind box, positioned to affect the throwing action of said first-mentioned means in each of said wind boxes.
25. In a blowing machine for fur, in combination, a plurality of consecutive wind boxes, means in each of said wind boxes adapted to receive and throw fur particles upwardly thereinto and to throw downwardly heavier fur particles, a perforated rotating drum for each of said wind boxes and positioned to receive upwardly thrown fur particles and rotatable in a direction to carry the fur particles in a direction toward the next succeeding wind box, each wind box and its associated perforated drum being arranged so that the latter is the only perforated surface into contact with which fur particles are thrown, and an adjustable plate-like member, one for each wind box, positioned to affect the throwing action of said first-mentioned means in each of said wind boxes.
26. In a blowing machine for fur, in combination, a plurality of consecutive wind boxes, means in each of said wind boxes adapted to receive and throw fur particles upwardly thereinto and to throw downwardly heavier fur particles, a perforated rotating drum for each of said wind boxes and positioned to receive upwardly thrown fur particles and rotatable in a direction to carry the fur particles in a direction toward the next succeeding wind box, a second rotating drum, one for each wind box but imperforate and positioned substantially underneath the perforated rotating drum therein and adapted to receive fur particles from said perforated drum, said imperforate drum being rotatable in a direction to carry fur particles received thereon to said first-mentioned means associated with the next succeeding wind box, each wind box and its associated perforated drum being arranged so that the latter is the only perforated surface into contact with which fur particles may be thrown, and a plate-like member, one for each wind box, positioned to affect the throwing action of said first-mentioned means in each of said wind boxes.

In testimony whereof I affix my signature.

FRANZ BRÜCKNER.
